UNITED STATES PATENT OFFICE.

EMERSON P. JENNINGS, OF LEHIGHTON, PENNSYLVANIA.

SHEET-SUPPORTING DEVICE.

1,392,061.

Specification of Letters Patent. Patented Sept. 27, 1921.

Original application filed March 30, 1916, Serial No. 87,725. Divided and this application filed November 24, 1919. Serial No. 340,153.

To all whom it may concern:

Be it known that I, EMERSON P. JENNINGS, a citizen of the United States, residing at Lehighton, in the county of Carbon and State of Pennsylvania, have invented certain new and useful Improvements in Sheet-Supporting Devices, of which the following is a specification, reference being had thereto to the accompanying drawings.

10 This invention relates to a tympan gage, or sheet supporting device, for use in sheet feeding devices for printing presses, and is a division of the application for patent on sheet feeding mechanism filed by me March 15 30, 1916, Serial No. 87,725.

The object of the invention is to provide a gage or supporting device which will accurately position a sheet upon the platen and which will be automatically withdrawn to permit the removal of the sheet; to provide such a device which will be positively operated from the coöperating parts of the press and sheet feeding mechanism; and, further, to provide such a device which will be simple and durable in construction and certain in its operation. Other objects of the invention will appear as the mechanism is described in detail.

In the accompanying drawings Figure 1 is a side elevation, partly broken away, of a printing press, showing my invention applied thereto; Fig. 2 is a bottom plan view of the platen showing the sheet supporting device attached thereto; Fig. 3 is a sectional view showing the slidable bearing for the finger shaft and the spring for actuating the latter; Fig. 4 is a sectional view showing the retaining device; Fig. 5 is a detail view showing the tripping mechanism, with the parts separated; and Fig. 6 is a side elevation of a portion of the platen showing the mechanism applied thereto.

In these drawings I have illustrated one embodiment of my invention and have shown the same as forming a part of the sheet feeding mechanism described in the above mentioned application, and applied to a printing press comprising a normally fixed platen and having a form-bed mounted for movement in a right line toward and from the platen, but it will be understood that this

particular embodiment is shown for the purpose of illustration only and that the invention is applicable to feeding mechanisms and presses of various kinds.

As shown in the present drawings the press comprises a main frame consisting of side members 1 between which is mounted a normally fixed platen 2, and which are provided with guide-ways 3 having slidably mounted therein blocks 4 which carry a combined form-bed and inking drum 5. The guide blocks, and consequently the combined form-bed and inking drum are moved along the guide-ways in a right line toward and from the platen by means of pitmen 6 which are connected with crank wheels, which are here shown as gears 7 meshing with a pinion 8 carried by a shaft 9 which may be connected with any suitable source of power. 70 Mounted on the main frame but above the platen 2 is a sheet separating device 10. This device, obviously, forms no part of the present invention and it need not be described in detail as a full 75 description thereof will be found in the above mentioned application. Suffice it to say that the mechanism operates to separate the edge of the lowermost sheet from a pile of sheets and to move the same into a position to be gripped by conveying grippers 11, mounted for movement across the face of the platen. The conveying mechanism is also fully described in the above mentioned application and will be described here only to 85 the extent which it enters into coöperation with the tympan gage. The conveying grippers are carried by reciprocating rack bars 12 mounted on opposite sides of the platen and meshing with gears 13 mounted on a 90 shaft 14, on which is also mounted a pinion 15 meshing with a rack bar 16 connected with the form-bed, preferably by securing one end of the rack bar to one of the slide blocks 4. Coöperating with the conveying 95 mechanism are platen grippers, 17, which are in the form of depending fingers carried by slide bars 18 which are provided with studs 19 arranged to enter grooves in cam plates 20 carried by the rack bars 12, where- 100 by the platen grippers are moved into and out of engagement with the sheet in timed

relation to the movement of the other parts of the mechanism. The feeding mechanism also comprises delivery grippers 21 which are carried by L-shaped arms 22 mounted 5 on a shaft 23 to which rocking movement is imparted to move the grippers toward and from the lower edge of the platen, this movement being preferably imparted to the shaft through means of a sprocket wheel and 10 chain connection with the shaft 14. Suitable mechanism is provided for opening and closing the jaws of the delivery grippers at the proper times to cause them to grip the lower edge of the sheet which is on the 15 platen so that the sheet may be withdrawn thereby upon the rearward movement of the arms 22.

It is desirable that stops or supporting devices of some kind be provided to accurately position the sheet upon the face 20 of the platen when it is fed thereto by the conveying mechanism, and further that these devices should be moved out of the path of the sheet to permit the same to be moved 25 across the lower edge of the platen by the delivery mechanism. This support may be of any suitable character which will properly engage and support the sheet, and which will not interfere either with the operation 30 of the delivery devices, or with the movement of the form. In the present construction I have provided a supporting device which is arranged normally in a position to support the sheet, and is automatically 35 moved out of its supporting position to permit the removal of the sheet by the delivery mechanism. As here shown this device comprises a shaft 24 mounted adjacent to, and preferably just below the lower edge of the 40 platen, and arranged for both rotatory movement and for bodily transverse movement. These movements may be secured in different ways, but preferably the shaft is mounted in elongated bearings 25 secured to the lower 45 edge of the platen. Mounted on the shaft 24 and arranged at intervals along its length are a plurality of supporting devices or gages, so arranged that when the shaft is in its normal position they will project beyond 50 the face of the platen and beyond the tympan which is carried thereby, and will receive the lower edge of the sheet which is on the platen and limit its downward movement. Each supporting device preferably 55 comprises a supporting finger 26 rigidly secured to the shaft and so arranged with relation to the lower edge of the platen that the edge of the sheet when in engagement therewith will extend slightly beyond said 60 lower edge of said platen to permit it to be engaged by the delivery grippers. I have also shown in connection with each supporting device a second finger, 27, which is curved upwardly to a point in front of the 65 tympan and so arranged that it can be

moved into engagement with the lower portion of the sheet to hold the same against the tympan during the taking of the impression. Any suitable means may be employed for retaining the shaft in its normal 70 position and, in the present instance, a spring 28 is coiled about the shaft near one end thereof and serves to retain the same normally in a position to support the fingers 26 in substantially horizontal positions, and 75 other devices act on the shaft to hold the same normally in its foremost position so that the ends of the upwardly curved fingers 27 will be spaced a short distance from the face of the tympan to enable the sheet to 80 pass between the same and the tympan. These last-mentioned devices are preferably two in number and each comprises a finger 29 having its upper end arranged to bear 85 against a slide bar 30 connected with the shaft 24. The lower end of the finger 29 bears against the adjacent portion of a depending arm, or plate, 31, secured to the adjacent bearing 25 and the point of contact between the bearing and the plate constitutes 90 a fulcrum about which the finger is moved. The finger itself may be resilient, but I prefer to utilize a supplemental spring and have here shown a bolt 32 extending through the finger 29 and the depending plate 31, 95 with its head bearing against the rear surface of the finger, and having a spring 33 coiled about the same between the forward surface of the plate 31 and the nut 34 on the forward end of the bolt. The tension 100 of the spring is thus exerted on the shaft through the finger 29 and the slide bar 30, and this tension may be regulated by adjusting the position of the nut 34 on the bolt. The shaft is moved rearwardly to carry the 105 fingers 27 into engagement with the sheet just prior to the contact of the form with the sheet, and this movement is preferably accomplished by the form-bed, or a part carried thereby. In the construction here shown 110 slide bars 35 are secured to the respective ends of the shaft, near the outer ends of the bearings 25, and are arranged in the path of a part carried by the form-bed, such as the type chase. The slide bars project such a 115 distance in front of the form that sufficient movement will be imparted thereto by the form-bed to cause the fingers to engage the sheet just in advance of the taking of the impression. The resiliency of the fingers 27 120 enables a further sliding movement to be imparted to the shaft after the fingers have engaged the sheet, to enable the form to come in contact with the sheet, and the bars 35 are preferably provided with adjusting 125 devices, such as set screws 36, by means of which the amount of movement imparted thereto by the form-bed can be regulated. In the operation of the press the movement of the parts is so timed that during the 130

taking of the impression the conveying grippers will be below the platen and the delivery grippers will be in their retracted positions. As the form-bed begins to move 5 outwardly after the taking of the impression the conveying grippers move upwardly and the delivery grippers move toward the platen so that when the form-bed reaches the outer limit of its movement the conveying 10 grippers will have gripped another sheet at the separating device and the delivery grippers will have gripped the lower edge of the sheet on the platen. Means are, therefore, provided to hold the shaft 24 in its retracted 15 position until the delivery grippers have engaged the edge of the sheet. To accomplish this suitable detent devices are provided each of which, as here shown, comprises a collar 37 having on the lower side thereof 20 a shoulder 38 and provided with a guide pin, or rod, 39, slidably mounted in a guideway formed in a bearing block 40 secured to and depending from the platen. Mounted on the lower edge of the bearing block 40 25 is a resilient finger 41 having at its forward end a shoulder 42 adapted to engage the shoulder 38 of the collar on the shaft when the latter is in its retracted position. The shoulder on the resilient finger 41 extends 30 laterally beyond the collar 37 and into the path of a cam 43 mounted on the shaft adjacent to the collar 37 and adapted to move the shoulder 42 into an inoperative position when the shaft is rotated, as will be herein- 35 after described, thus releasing the shaft and permitting it to be moved forwardly under the influence of the spring actuated devices 29. Means are provided for rotating the shaft to carry the supporting fingers out of 40 the path of the sheet before the delivery grippers begin their rearward movement. While this may be accomplished in various ways I preferably employ one of the vertically movable rack bars, which carry the 45 conveying grippers, to impart turning movement to the shaft. I have, therefore, secured to the lower portion of one of these bars a cam plate 44 and have mounted on the end of the shaft adjacent to the rack bar 50 carrying said cam plate a trip arm 45 which is so connected with the shaft 24 that it will yield to permit the cam plate 44 to pass the same upon the upward movement of the rack bar and it will be engaged and actuated by 55 said cam plate upon the first portion of the downward movement of the rack bar, thus rocking the shaft and moving the supporting fingers into their inoperative positions. Because of the slack in the sprocket chain by 60 means of which the delivery grippers are operated these grippers do not begin to move immediately upon the downward movement of the rack bars, and this slight interval of time is sufficient to permit the movement of 65 the supporting fingers into their inoperative 70 positions before the delivery grippers begin to withdraw the sheet from the platen. While this trip arm may be connected with the shaft in any suitable manner I have found the arrangement here shown very efficient. The arm 45 is pivotally mounted at one end upon a pin 46 carried by a collar 47 mounted on and rigidly secured to the adjacent end of the shaft 44. The trip arm is provided with a transversely elongated opening 48 to receive the reduced end of the shaft 24, which projects beyond the collar 47 and which forms a fulcrum about which the arm rotates to actuate the collar 47 and the shaft 24. This elongated opening permits of the upward movement of the trip arm to enable the cam plate to pass the same on its upward movement, and a spring 50 mounted in a slot 49 in the trip arm serves to return the latter to its normal position 80 after the cam plate has passed the same, so that the arm will lie in the path of the plate when the latter begins its downward movement. The cam plate 44 holds the supporting fingers in their retracted positions until 85 the sheet has been withdrawn and the shaft is then released to permit the return of the fingers to their normal positions, the detents 41 having been released when the shaft is rotated, to permit of the forward movement 90 of the same.

The operation of the device will be readily understood from the foregoing description of the several parts thereof, and I wish it to be understood that I do not desire to be limited to the details shown and described as various modifications will occur to one skilled in the art.

Having now fully described my invention, what I claim as new and desire to secure by Letters Patent, is:—

1. The combination with a printing couple comprising a fixed member and a movable member arranged with their operative faces in substantially vertical planes, of a sheet 110 supporting device mounted near the lower edge of said fixed member for movement into a position wholly in the rear of the plane of the face of said fixed member or into a position intersecting said plane, and 115 having a part movable into and out of holding engagement with a sheet supported by said device, and means for controlling the movement of said part in timed relation to the movement of said movable member. 120
2. The combination with a printing couple comprising a fixed member and a movable member, of a sheet supporting device arranged near the lower edge of said fixed member and having a part movable into a 125 position wholly in the rear of the plane of the face of said fixed member or into a position intersecting said plane, and having another part movable into a position to engage the face of the sheet near the lower edge 130

thereof when the first mentioned part is in a position intersecting said plane, and means for controlling the movement of said parts in timed relation to the movement of 5 said movable member.

3. The combination with a printing couple comprising a fixed member and a movable member, of a sheet supporting device arranged near the lower edge of said fixed member and having a part movable into a position wholly in the rear of the plane of the face of said fixed member or into a position intersecting said plane, and having another part movable into a position to engage the 10 face of the sheet near the lower edge thereof when the first mentioned part is in a position intersecting said plane, and means for moving said sheet supporting device in one direction to cause the last mentioned part 15 to engage the sheet and for moving said sheet supporting device in another direction to move both of said parts into positions to permit the movement of the sheet across the lower edge of said fixed member.

4. The combination with a printing couple, comprising a fixed member and a movable member, of a sheet supporting device arranged near the lower edge of said fixed member and having a part movable into and 20 out of supporting position, and having another part movable into and out of position to engage the face of the sheet near the lower edge thereof, a device connected with said last-mentioned part and arranged in 25 the path of said movable member to move said part into operative position, and an operative connection between said movable member and said sheet supporting device to move both of said parts away from the edge 30 of said fixed member.

5. The combination with a printing couple, comprising a fixed member and a movable member, of a sheet supporting device pivotally supported near the lower edge of said 40 fixed member and having a part movable into and out of supporting position, means for holding said part in supporting position, and other means for imparting pivotal movement to said sheet supporting device to move 45 said part into an operative position.

6. The combination with a printing couple, comprising a fixed member and a movable member, and a sheet conveying device movable across the face of said fixed member, 50 of a sheet supporting device mounted near the lower edge of said fixed member and having a part movable into and out of supporting position, means for holding said part in supporting position, and means 55 actuated by said sheet conveying device to move said part into an inoperative position.

7. The combination with a printing couple, comprising a fixed member and a movable member, and a sheet delivery device to remove 60 the printed sheet from said fixed

member, of a sheet supporting device arranged near the lower edge of said fixed member and having a part movable into and out of supporting position, means to hold said part in said position, and means 70 to move said part into inoperative position after said delivery device has gripped the sheet and before it has begun its delivery movement.

8. The combination with a printing couple, 75 comprising a fixed member and a movable member, of a sheet supporting device arranged near the lower edge of said fixed member and having a part capable of both a pivotal movement and a bodily movement 80 transversely to the face of said fixed member, and means for causing both of said movements in timed relation to the movement of said movable member.

9. The combination with a printing couple, 85 comprising a fixed member and a movable member, of a sheet supporting device arranged near the lower edge of said fixed member and having a part supported normally in a position to support the sheet on 90 said fixed member and having another part arranged to be moved into and out of a position to engage the lower edge of said sheet, said sheet supporting device being capable of bodily movement transversely to the face 95 of said fixed member to move the last-mentioned part into engagement with the sheet, and being capable of pivotal movement to move both of said parts into inoperative positions, and means for causing both of 100 said movements in timed relation to the movement of said movable member.

10. The combination with a printing couple, comprising a fixed member and a movable member, of a sheet supporting device 105 comprising a shaft mounted near the lower edge of said fixed member for both rotatory movement and bodily movement transversely to its length, fingers carried by said shaft, means for holding said fingers normally in 110 positions to support a sheet in front of said fixed member, and means actuated in timed relation with the movable member of said printing couple to impart bodily movement to said shaft and to rotate the same to move 115 said fingers into their inoperative positions.

11. The combination with a printing couple, comprising a fixed member and a movable member, of a sheet supporting device comprising a shaft mounted near the lower 120 edge of said fixed member for both rotatory movement and bodily movement transversely to its length, fingers carried by said shaft and means for holding said fingers normally in positions to support a sheet in front of 125 said fixed member, means actuated in timed relation with the movable member of said printing couple to impart bodily movement to said shaft and to rotate the same to move said fingers into their inoperative positions, 130

- springs tending to move said shaft toward its normal position, a detent to retain said shaft in its rearward position, and means actuated by the rotary movement of said shaft to release said detent and permit said springs to move said shaft to its forward or normal position.
12. The combination with a printing couple, comprising a fixed member and a movable member, of a sheet supporting device comprising a shaft mounted near the lower edge of said fixed member for both rotatory movement and transverse sliding movement, fingers carried by said shaft to support the sheet and retain the lower edge thereof in engagement with said fixed member, means arranged in the path of said movable member to impart transverse movement to said shaft, and means operatively connected with said movable member to impart rotatory movement to said shaft.
13. The combination with a printing couple, comprising a fixed member and a movable member, of a sheet supporting device comprising a shaft mounted near the lower edge of said fixed member for both rotatory movement and bodily movement transversely to the same, fingers carried by said shaft to engage the lower portion of a sheet and support the same in proper relation to said fixed member, springs tending to hold said shaft normally in its foremost position and to hold said fingers in their operative positions, means arranged in the path of the movable member of said printing couple to impart transverse movement to said shaft, a trip finger connected with said shaft to impart rotatory movement thereto, and an actuating member arranged to operatively engage said trip finger and operatively connected with said movable member.
14. The combination with a printing couple, comprising a fixed member and a rotatory member, of a sheet supporting device comprising a shaft mounted at the lower edge of said fixed member for both rotatory movement and bodily transverse movement, a series of fingers secured to said shaft and arranged to project beyond the face of said fixed member and support the sheet in front thereof, a spring acting on said shaft to hold said fingers normally in their supporting positions, other fingers secured to said shaft and adapted to extend above the lower edge of said fixed member when the first-mentioned fingers are in their supporting positions, springs to hold said shaft normally in its foremost position, parts connected with said shaft and arranged in the path of said movable member to move said shaft rearwardly, a detent to hold said shaft in its rearmost position, means carried by said shaft to release said detent when rotatory movement is imparted to said shaft, and an actuating device to impart rotatory move-
- ment to said shaft, said actuating device being operatively connected with said movable member.
15. The combination with a normally stationary member of a printing couple, and means to feed a sheet to and from printing position with relation to said member, of a device mounted near one edge of said member and movable into the path of said sheet to position the same with relation to said member and into engagement with the face of said sheet to hold it in said position, and means controlled by said feeding mechanism to move said device out of the path of said sheet to permit the latter to be withdrawn from said member.
16. The combination with a normally stationary member of a printing couple, and means to feed a sheet to and from printing position with relation to said member, of a device mounted near one edge of said member and movable first into the path of said sheet to limit its movement relatively to said member, then into gripping engagement with said sheet, and then out of the path of said sheet, and means controlled by said feeding means to actuate said device.
17. The combination with a normally stationary member of a printing couple and means to feed a sheet to and from printing position with relation to said member, of a device mounted near one edge of said member and movable into the path of said sheet to position the same with relation to said member, and comprising a part pivotally mounted and arranged to be moved into engagement with said sheet to clamp the same against the face of said member upon one movement of said device, and to be moved about its axis into a position beyond the edge of said member upon another movement of said device, and means controlled by said feeding means to actuate said device.
18. In a printing press the combination with a stationary member of a printing couple, of a shaft mounted at the lower edge of said stationary member for bodily movement transversely thereto, and sheet supporting members connected with said shaft and movable thereby into and out of the path of a sheet as the latter is moved onto and off said stationary member.
19. In a printing press the combination with a stationary member of a printing couple, of a rotatable shaft mounted at the lower edge of said stationary member for movement transversely thereto, and sheet supporting members connected with said shaft and movable thereby into and out of the path of a sheet as the latter is fed onto and off said stationary member.
20. In a printing press, the combination with a stationary member of a printing couple, of a sheet supporting device mounted

at the lower edge of said stationary member for bodily movement transversely to the edge of the stationary member and for pivotal movement about an axis parallel with the face of said stationary member, and means for actuating said sheet supporting device.

21. In a printing press, the combination with a stationary member of a printing couple, of a plurality of supporting devices mounted at the lower edge of said stationary member for movement into and out of the plane of the face thereof, means for causing said devices to project beyond the face of said stationary member to receive a sheet, for moving said devices into holding engagement with said sheet and for withdrawing said devices.

22. In a printing press, the combination with a stationary member of a printing couple, of a series of fingers arranged at the lower edge of said stationary member and mounted for both sliding and pivotal movement, means for causing said fingers to project beyond the face of the stationary member to receive the sheet, to move the same

into clamping engagement with said sheet, and to rock the same about a common axis to move them out of the path of said sheet.

23. The combination with a normally stationary member of a printing couple having its face in a substantially vertical plane, of a device pivotally mounted adjacent to the lower edge of said member and having bodily movement transversely to the face thereof into a position to receive a sheet and support the same in proper relation to said member, and cam controlled means to actuate said device.

24. The combination with the stationary member of a printing couple, and means to feed a sheet to and from printing position with relation to said member, of a device mounted near one edge of said member and movable into the path of said sheet to position the same with relation to said member, and a cam operatively connected with said feeding means to control the movement of said device.

In testimony whereof I hereunto affix my signature.

EMERSON P. JENNINGS.
